UNITED STATES PATENT OFFICE.

THOMAS MCK. NOYES, OF BINGHAMTON, NEW YORK, ASSIGNOR TO NOYES COMB COMPANY, OF BINGHAMTON, NEW YORK, A CORPORATION OF NEW YORK.

COMB.

1,396,275.

Specification of Letters Patent.

Patented Nov. 8, 1921.

Application filed August 4, 1921. Serial No. 489,761.

To all whom it may concern:

Be it known that I, THOMAS MCKECHNIE NOYES, a citizen of the United States, residing at Binghamton, county of Broome, and 5 State of New York, have invented certain new and useful Improvements in Combs, of which the following is a specification.

This invention relates to dressing combs, and is in the nature of an improvement in 10 the construction and arrangement disclosed by United States Patent No. 531,468, issued to Joseph P. Noyes, under date of December 25th, 1894.

In the manufacture of combs from the 15 horns of cattle, there has heretofore been an objectionably large waste of both material and labor. Part of such waste has arisen because of breakage of combs during processes of manufacture and resulting from de- 20 fects in the material or from unskilful or careless handling thereof during the cutting of teeth therein. The greater portion of such waste of material has arisen because of the fact that, even in the case of large horns, 25 after cutting the stock as economically as possible for the production of one piece combs therefrom, there remains many smaller pieces of material which would be available for the production of two or three 30 piece combs. In the cases of smaller horns, the proportion of such waste material to that which may be utilized for one piece combs is greater than in the case of larger horns.

For many years the cost of horns has been 35 gradually increasing and, because of the general practice of dehorning cattle, it has become commercially impracticable to secure an adequate supply of the larger sizes 40 of horns which were formerly obtainable in abundance. For these reasons, the utilization of portions of broken one piece combs as well as pieces of material which are too small to be available for the production of 45 one piece combs has become an increasingly pressing problem to manufacturers of horn combs, and the prior patent hereinbefore referred to well exemplifies the efforts which have heretofore been made toward the utilization 50 of such pieces and material in marketable combs.

In such prior patent means was disclosed for utilizing two pieces of toothed material in manufacturing a single comb, which 55 means comprised a band passing between

contiguous teeth of abutting ends of such two pieces and passing outside of the metal back of the comb. As pointed out in such prior patent, a band so passing outside of the comb back is generally considered un- 60 sightly, and the sale of such combs has been greatly curtailed because the presence of such bands is rarely tolerated by purchasers, other than when such bands are utilized for the further purpose of providing attaching 65 means for a retaining chain or cord.

But a very small proportion of the total 70 number of combs sold are utilized in public wash rooms, or the like, where the use of retaining means is necessary or desirable, and it has been observed that combs having 75 such fastening means are avoided for use other than in such public places, not only because the possession of such combs may be facetiously or maliciously characterized as indicating theft thereof from some public 80 wash room, but for the further reason that combs so equipped are less convenient to use or carry in a pocket or traveling bag, occupy more room, and will be more likely to catch on and injure surrounding objects. For the foregoing and other reasons the sale of 85 combs embodying the disclosure of said prior patent has been, in effect, restricted to purchases for use in public wash rooms, and the like; hence, it has been impracticable to profitably utilize more than an insignificantly small portion of the pieces of combs 90 broken during manufacture and of the comparatively small pieces of horn material which are left over after making one-piece horn combs.

The object of this invention is to provide a comb comprising two or more toothed pieces so joined that said pieces will not be 95 permitted to appreciably alter their relative positions in consequence of shrinkage, in which the joints will be so covered that the hair of the user or other surrounding objects will not be permitted to catch in such 100 joints or on the covering provided therefor, so that the labor cost for the manufacture of the parts and their assembly will not exceed that for prior forms of combs, and so that the appearance of the means employed for 105 uniting such pieces and covering the joints therebetween will not impair the marketability of such combs.

This invention consists of certain features of construction and arrangement of parts 110

which are shown in the annexed drawing, hereinafter fully described, and more particularly pointed out in the claims.

Similar reference characters denote like parts throughout the accompanying drawing, in which—

Figure 1 is a side view of a completed comb embodying this invention;

Fig. 2 is a fragmentary perspective view 10 of the comb of Fig. 1, with a portion of the metal back broken away to disclose the formation and arrangement of the parts thereunder;

Fig. 3 is an enlarged cross section of the 15 comb of Fig. 1, taken on the line 3—3 thereof; and,

Fig. 4 is a fragmentary view of the toothed edge of the comb of Fig. 1.

The comb shown in Fig. 1 comprises the 20 toothed pieces A and B, which pieces are mounted in the metallic back C, and the abutting ends of which pieces are retained in intended relative positions by the connector D.

As best indicated by Figs. 2 and 3, both 25 sides of the backs of the toothed pieces A and B have grooves formed lengthwise thereof, such as the grooves E shown in Fig. 2, for receiving the edges of the metal back 30 piece C. The metal back piece C will give best results when made of a somewhat resilient material (such as, for example, spring temper sheet brass) so that anticipated shrinkage of the toothed pieces will be so followed up by the edges of said back as to 35 avoid disengagement therefrom.

The connector D has openings, such as the 40 openings f and g, for snugly receiving the teeth at the adjacent ends of the pieces A and B, and said connector is closely formed around the backs of said toothed pieces, as best shown by Fig. 3.

When the back C is applied to the toothed 45 pieces A and B, the portions of the edges of the piece C which engage the connector D press the sides of said connector into the grooves E formed in the sides of the toothed pieces A and B, as best indicated by Fig. 3, and such engaging edges of the back piece 50 C will be sprung somewhat apart where engaging the sides of the connector D, as best illustrated by Fig. 4.

If adequate pressure is applied to the 55 edges of the back C during the assembly of the comb, as just described, the edges of said back C will be closely fitted into the grooves E and over the connector D so as to provide a very neat and satisfactory appearance, and so that there will be no sharp edges or 60 interstices such as would tear or catch upon the hair of a user.

Although I have shown but two toothed pieces, it will be apparent to those skilled in this art that three or more such pieces 65 may be similarly joined, and that this in-

vention may be readily employed for joining a coarse end tooth of a piece such as the piece A with a fine end tooth such as the fine teeth of the piece B or for joining two such fine teeth, as well as for joining two coarse teeth as shown.

In Figs. 2, 3 and 4 the thickness of the conductor D and the distortions of the contours of the various pieces are somewhat exaggerated for purposes of illustration. In 75 practising this invention, it should be understood that the material of the connector D may be comparatively thin, without impairing the effectiveness of said connector in maintaining proper relationship between the 80 pieces A and B. The distortion of the outlines of the edges of the back C will, under such circumstances, be so slight, that same will be inappreciable, other than upon very careful inspection; and the connector D may 85 be most readily pressed into the grooves E when said back is made of comparatively thin material.

What I claim and desire to secure by Letters Patent of the United States of America is:

1. A comb comprising,—abutting pieces the adjacent ends of each of which pieces are toothed and the backs of which pieces are channeled to receive the edges of a metal 95 back; in combination with a connector engaging the teeth of such adjacent ends, engaging the sides of the backs of said pieces and entering the channels formed therein; and a metal back inclosing the backs of said 100 pieces and the ends of said connector, the edges of said back being so formed as to snugly engage the channeled portions of the backs of said pieces where not covered by said connector and to pass outside of the 105 portions of said connector which engage said channels and thereby force said connector portions somewhat into said channels.

2. A comb comprising,—abutting pieces the adjacent ends of which pieces are toothed and the backs of which pieces are channeled to receive the edges of a metal back; in combination with a connector engaging teeth of such adjacent ends, engaging the sides of the backs of said pieces and entering the channels formed therein; and a metal back inclosing the backs of said pieces and the ends of said connector, the edges of said back being so formed as to snugly engage the channeled portions of the backs of said 115 pieces where not covered by said connector.

3. A comb comprising,—abutting pieces the adjacent ends of each of which pieces are toothed and the backs of which pieces are channeled to receive the edges of a metal back; in combination with a connector consisting of a strip of comparatively thin sheet metal so formed as to cover the joint between and to engage teeth of said adjacent ends so as to maintain intended spacing therebe- 130

tween, and to engage the channels of said pieces at both sides of the joints therebetween; and a metal back inclosing the backs of said pieces and the ends of said strip.

5 4. A comb comprising,—abutting pieces the adjacent ends of which are toothed, in combination with a connector engaging teeth

of such adjacent ends and the sides of the backs of said pieces, and a metal back inclosing the backs of such pieces and the ends of 10 said connector.

In witness whereof, I hereunto subscribe my name, this 2nd day of August 1921.

THOMAS MCK. NOYES.
